OTTO STIETZ, OF NEW YORK, N. Y.

Letters Patent No. 64,807, dated May 14, 1867.

IMPROVEMENT IN MAKING GLASS LETTERS, NUMBERS, &c.

The Schedule referred to in these Letters Patent and making part of the same.

TO ALL WHOM IT MAY CONCERN:

Be it known that I, OTTO STIETZ, of the city, county, and State of New York, have invented a new and useful Improvement in Glass Letters, &c.; and I do hereby declare the following to be a full, clear, and exact description of the nature, construction, and operation of the same, sufficient to enable one skilled in the art to which it appertains to construct and use the same, reference being had to the accompanying drawings, which are made part of this specification, and in which the same letters indicate similar parts.

Figure 1 is a face view.

Figure 2 is a section on the line *a b*, fig. 1.

The object of the invention is to give an apparent relief to the gilt face of the letters without affecting the plain surface of the glass on whose rear the letter is attached. It is accomplished by etching in the face of the letter on the reverse side of the glass, and causing the foil or metallic leaf laid thereupon to overlap upon the unetched or plain surface of the glass.

In the drawings, A represents the plate of glass, and B the face of the letter, which is etched in on the reverse side by means of fluoric acid. The action of the acid upon the glass has the effect of giving it a dull, dead, or frosted surface, and the metal C being laid upon it, and lapping upon the plain or unfrosted surface, forms a brighter band around the comparatively dead face of the letter, and gives the effect of a bevel edge and an appearance of saliency to the letter. Among the advantages of this mode of forming letters and figures may be cited that they are more easily constructed than letters in which the edge of the glass letters is bevelled to give the required relief. They are also much more easily cleansed than letters which have pieces of the edge cut out, or pieces bored or ground out of the centre, as in the letters O, D, R, B, &c., besides which many letters are fractured in the operation. The openings afford places for dirt to accumulate and for wet to leak in behind the glass, and loosen the cement by which they are fastened; and letters so formed are inferior in regard to cheapness, cleanliness, and safety, to those formed according to my improvement.

Having thus described my invention, what I claim as new, and desire to secure by Letters Patent, is—

A letter formed upon the reverse side of a piece of glass, by means of etching in the face of the letter and covering it with a surface of metal or foiling, lapping upon the unetched portion, thereby producing an appearance of relief, substantially as described.

To the above specification of my invention I have signed my name this 20th day of February, 1867.

OTTO STIETZ.
